UNITED STATES PATENT OFFICE

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE

OSCILLATORY SUPPORT FOR MOTION PICTURE PROJECTION MACHINES

Application filed September 30, 1927. Serial No. 222,971.

This invention relates to machine supports, and more particularly to an adjustable support for picture projecting apparatus and the like which require extreme rigidity and minute adjustment.

5 Motion picture projecting machines are commonly operated in such position that the line of projection is required to extend forwardly and downwardly. It is necessary, therefore, to provide a rigid means for supporting the machine whereby undesirable vibrations and consequent shaking of the picture may be prevented and to provide means for adjusting the angle of projection so that the picture may be directed upon a distant screen.

In accordance with the present invention the various elements of the machine are supported upon a transverse frame which is pivotally mounted upon an upright standard or pedestal. The pivotal connection is preferably located between the lamp house and the projection head so that the machine will be inherently partly balanced. The weight of the lamp house is sufficiently great, however, to require extra supporting means in order to prevent any undue strain from being placed upon the pedestal.

30 This invention also provides an auxiliary supporting member attached to the frame at a point near the rear end of the lamp house and extending downwardly at an angle to the supporting pedestal, the lower end thereof being joined to a suitable base. The distance between the auxiliary support and pedestal is greater at the base than at the upper end, whereby an increased rigidity is obtained and the tendency of the machine to tip or shake is reduced.

35 The point of attachment of the support to the frame may be varied longitudinally of the frame to provide for lamp houses of various sizes which are commonly constructed with feet differently located.

40 The invention also consists in certain new and original features of construction and combinations of parts hereinafter set forth and claimed.

45 Although the novel features which are believed to be characteristic of this invention

will be particularly pointed out in the claims appended hereto, the invention itself, as to its objects and advantages, the mode of its operation and the manner of its organization may be better understood by referring to the following description taken in connection with the accompanying drawings forming a part thereof, in which

55 Fig. 1 is a side elevation of a support for a motion picture projecting apparatus constructed in accordance with this invention;

60 Fig. 2 is a rear elevation thereof;

65 Fig. 3 is a section taken on the line 3—3 of Fig. 1 showing the frame and connecting means;

Fig. 4 is a section taken on line 4—4 of Fig. 1 showing the connection for the adjusting strut;

70 Fig. 5 is a side elevation of a modified form of support;

Fig. 6 is a rear elevation thereof, and

75 Fig. 7 is a plan view of the adjusting strut and connecting means shown in Fig. 5.

Like reference characters denote like parts in the several figures of the drawings.

In the following description and in the claims parts will be identified by specific names for convenience, but they are intended to be as generic in their application to similar parts as the art will permit.

80 Referring to the drawings more in detail, the support which has been shown by way of example, as suitable for a motion picture projecting apparatus, comprises pedestal member 10 rigidly secured to and supported by a suitable base 11. Frame 13 (Figs. 1 and 3) is pivotally mounted at the upper portion of pedestal 10 and adapted to support various pieces of apparatus, such as lamp house 14, projection head 15 and co-operating film magazines comprising a motion picture projection machine (not shown).

85 An adjustable leg comprising stationary and movable members, (Figs. 1 and 2) is shown as extending between base 11 and the rear end of frame 13 for the purpose of adjusting and holding said frame 13 in any desired angular position.

90 An adjustable leg comprising stationary and movable members, (Figs. 1 and 2) is shown as extending between base 11 and the rear end of frame 13 for the purpose of adjusting and holding said frame 13 in any desired angular position.

95 The stationary member comprises a pair of rods 20 (Fig. 2) pivotally supported by

base 11, as by rod 21 passing through collars 22 secured to said rods 20 and collars 23 secured to said base 11. The upper ends of rods 20 are joined by frame 24 (Figs. 2 and 5 4) having tubular members 25 through which said rods 20 are extended. Said rods may be rigidly secured to said tubular members as by means of nuts 26 threaded thereon. Frame 24 comprises a transverse section 28 10 and a plurality of collars 29 extending therefrom for a purpose to be hereinafter set forth.

The movable member of the supporting leg comprises a pair of rods 30 joined at their lower end by frame 31, in which they are rigidly 15 secured. Frame 31 is provided with a pair of collars 32 in sliding engagement with rods 20. Rods 30 are pivotally connected at their upper ends to frame 13 by rod 34 extending through collars 35 on said rods 30 and collars 36 which are provided with a transverse bore 37 (Fig. 3) for slidably engaging said frame. Threaded rod 40 extends parallel to rods 30 and is supported at its two ends by frame 31 and rod 34 respectively.

25 Rods 30 are extended through collars 41 forming a part of frame 24, and are adapted to slide longitudinally therein. Rod 40 is extended through internally threaded member 42 journaled in frame 24 by means of 30 bearings 43. Threaded member 42 may be rotated as by gear wheel 44 (Fig. 4) which is rigidly secured thereto, and co-operates with worm gear 45 carried upon shaft 46. Said shaft 46 may be journaled in collars 29 35 aforementioned extended from transverse member 28 of frame 24 and may be rotated by suitable hand wheels 47 located at the ends thereof.

An adjusting strut comprising a pair of 40 rods 50 (Figs. 1, 3 and 4) is extended between pedestal 10 and frame 24 forming a part of the above mentioned adjustable leg. Rods 50 may be journaled on rod 46 as by collars 51 and may be secured to pedestal 10 by means 45 of yoke 52 pivotally connected to said pedestal as at 53. Rods 50 may be provided with threaded ends which are extended through collars 54 attached to said yoke 52 and adjusted therein as by adjusting nuts 55.

50 In the operation of the apparatus thus far described, frame 13 may be pivotally moved about pedestal 10 for adjusting the angular projection of the device by suitable rotation of hand wheel 47, which by means 55 of worm gear 45 and gear wheel 44 serves to rotate threaded member 42 and thereby move threaded rod 40 longitudinally thereof. Rod 40 forming a part of the movable member of the adjustable leg, will cause rods 20 and 30 60 to be slidably displaced through collars 32 and 41. The leg may consequently be extended by a suitable amount to cause frame 13 to assume the angle desired.

Inasmuch as collars 36 will slide longitudinally on frame 13 as the same is tilted, it may

become necessary to adjust the distance between said collars and the pedestal 10 to avoid the same from interfering with the feet of the lamp house 14. This adjustment may be accomplished by nuts 55 co-operating with 70 the threaded ends of adjusting struts 50 whereby the strut may be changed in length as desired. This adjustment further provides the use of various size lamp houses having differently located feet, since the upper 75 end of the adjustable leg may be caused to assume any desired position with respect to frame 13.

In the modification shown in Figs. 5, 6 and 7, the various elements corresponding to those 80 disclosed in Figs. 1 to 4 have been given similar reference numerals and operate in a corresponding manner. The construction shown in Fig. 5, however, differs from that shown in Fig. 1 in that rods 30 are located 85 at the rear of rods 20 with respect to the line of projection of the machine, whereas in Fig. 1 the various elements are shown as being located in the same plane, frame 24 being changed accordingly. Since the various elements described in these figures, however, are substantially identical with and operate in a manner similar to those above set forth they will not be again described in detail.

The supporting means constructed in accordance with the present invention provides 95 for the interchangeable use of various forms and types of lamp houses. Furthermore, the line of projection may be readily and accurately adjusted by means of hand wheel 47 100 without interrupting the operation of the machine and the adjustment once made will be accurately maintained since the worm gear is substantially non-reversible unless positively moved by movement of hand wheel 47.

Increased stability is obtained by extending the adjustable leg at an incline to the supporting pedestal whereby the base of said leg is located at a greater distance from the pedestal than the top portion thereof. Since the 110 lamp house is frequently the heaviest part of a motion picture projecting machine, the adjustable leg being located directly under or adjacent to the lamp house serves as a firm support therefor and prevents vibrations 115 thereof.

In the drawings accompanying and forming part of this specification, a practical commercial embodiment of the invention is shown, but as such illustration is primarily 120 for purposes of disclosure, it will be understood that the structure may be modified in various respects without departure from the broad spirit and scope of the invention as hereinafter defined and claimed.

125 What is claimed is:

1. A machine support comprising a base, an upright pedestal secured thereto, a frame pivotally mounted on said pedestal for supporting said machine and an adjustable leg 130

extending between said frame and said base, said leg being extensible for varying the angularity of said frame, an adjustable link interconnecting said leg and said pedestal whereby the point of attachment of said leg may be varied.

2. In a motion picture projecting apparatus, an upright pedestal, a base member therefor, a frame pivotally supported thereby, an adjustable leg extending between said frame and said base, said leg being slidably extensible for varying the angularity of said frame and means for slidably adjusting said leg longitudinally on said frame.

15 3. In a machine support, an upright pedestal, a base member therefor, a frame pivotally supported thereby, an adjustable leg comprising a pair of members in sliding engagement, one of said members being pivotally secured to said base, and the other of said members being slidably connected to said frame for movement longitudinally thereof.

4. A machine support comprising an upright pedestal, a base member therefor, a frame pivotally supported thereby, an adjustable leg comprising a pair of members slidably connected together, one of said members being pivotally secured to said base, the other of said members being slidably connected to said frame for movement longitudinally thereof, and means for slidably moving said members with respect to each other for varying the angularity of said frame.

5. In a motion picture projecting apparatus, an upright pedestal, a base member therefor, a frame pivotally supported thereby by an adjustable leg comprising a pair of members slidably connected together, one of said members being pivotally secured to said base, the other of said members being slidably connected to said frame for movement longitudinally thereof, and means comprising a worm and cooperating gear wheel for slidably moving said members with respect to each other.

6. In a picture projecting apparatus, a support comprising an upright pedestal, a frame pivotally mounted thereon and adapted to support said apparatus, an inclined leg extending downwardly from said frame, comprising a pair of members in sliding engagement, means for extending said members for varying the angularity of said frame, comprising a threaded rod attached to one of said members, a cooperating rotatable threaded member attached to the other thereof, a link pivotally connected to said leg and to said pedestal and means for adjusting said link for varying the point of attachment of said leg to said frame.

7. In a picture projecting apparatus, an upright pedestal, a base member therefor, a frame pivotally supported by said pedestal, an adjustable leg comprising a pair of members slidably connected together, one of said

members being pivoted to said base, the other of said members being slidably secured to said frame for movement longitudinally thereof, means comprising a threaded rod secured to one of said members and an internally threaded member cooperating therewith for slidably moving said members, and an adjustable link interconnecting said leg and said pedestal for controlling the longitudinal position of said leg with respect to said frame.

8. A machine support comprising a base, an upright pedestal secured thereto, a frame pivotally mounted on said pedestal for supporting said machine and an adjustable leg extending between said frame and said base, said leg being extensible for varying the angularity of said frame, means for slidably connecting said leg to said frame for movement longitudinally thereof, and a link interconnecting said leg to said pedestal for controlling the longitudinal position of said leg with respect to said frame.

9. In a projection machine, a pedestal lever carrying the projection apparatus, a base substantially coextensive with said lever, a vertical pedestal pivotally carrying said lever and mounted directly under the pivot point thereof in a position to support the major portion of the weight of the apparatus, an extensible rear bracing frame comprising a pair of slidably adjustable sections extending between said lever and the rear portion of said base and means mounted between said sections for extending said frame to vary the angle of projection.

AUGUSTO DINA.
